UNITED STATES PATENT OFFICE

HERMAN V. VROOMAN, OF RACINE, WISCONSIN.

ASH SIFTER FOR FURNACES.

Application filed March 28, 1922. Serial No. 547,365.

To all whom it may concern:

Be it known that I, HERMAN V. VROOMAN, a citizen of the United States, and resident of Racine, in the county of Racine and State 5 of Wisconsin, have invented certain new and useful Improvements in Ash Sifters for Furnaces; and I do hereby declare that the following is a full, clear, and exact description thereof.

10 This invention pertains to attachments for furnaces and more particularly to a device adapted to sift the ashes as they are shaken from the grate.

15 The primary object of my invention resides in the provision of means adapted to be positioned within the ashpit of a furnace, whereby ashes shaken from the grate will be sifted and the unconsumed particles of fuel separated therefrom.

20 A more specific object, incidental to the foregoing, resides in the provision of a normally inclined screen hinged within the ashpit of a furnace for the purpose of sifting the ashes shaken from the grate, the same being adjustable to a substantially horizontal 25 position to permit convenient removal of the ashes from the ashpit.

With the foregoing and other objects in view, the invention consists in what is herein 30 shown and described and more particularly pointed out and defined by the appended claim, it being understood that various modifications in the mechanical details of construction are contemplated as within the 35 terms of the appended claim.

In the drawings:—

Figure 1 illustrates a sectional view through a portion of a conventional type of furnace, showing the invention positioned 40 therein, and

Figure 2 is a sectional view taken on the line 2—2 of Figure 1.

Referring now more particularly to the accompanying drawing, the numeral 1 designates a conventional type of furnace consisting of an outer casing 2 and provided with a fuel compartment 3 and shaker grate 4. Below the fuel compartment 3 is the customary ashpit 5 for receiving the ashes 45 shaken through the grate. While I have shown a specific structure of furnace for the purpose of illustrating the application of the invention, it will be readily appreciated that the same may be used in connection with 50 furnaces of the hot water, hot air, or steam types.

In the preferred embodiment of the invention, I propose to construct the same as an attachment separate from the furnace and adapted to be positioned within the ashpit 60 of the same without necessitating altering of the furnace. For this purpose I provide a pair of side standards 6 connected by means of cross members 7. The side standards 6 are spaced apart approximately the width of 65 the ashpit and are, therefore, positioned adjacent the sides of the pit, in which position they will in no way interfere with the removal of the ashes. Pivottally connected to the side standards 6, at its upper end, is a 70 normally inclined screen 8 adapted to be supported on the ground at its lower edge. The screen 8 is provided with upwardly extending sides 9 adapted to prevent large particles, which do not pass through the screen, 75 from rolling off to the side of the same.

While I have shown and described an inclined screen as constructed from woven wire, it is obvious that the same might be formed of perforated sheet metal, if so desired.

The free end of the inclined screen 8 is provided with means, preferably a loop 10, for the purpose of locking the screen in a substantially horizontal position parallel 85 with the grate 4. This is accomplished by passing the loop over a hook provided within the upper part of the ashpit, or in some instances, where the construction may permit, the loop may be passed over the ends of 90 the grate.

In operation the screen 8 is generally inclined, as illustrated in Figure 1 of the drawing, and in this position the ashes shaken through the grate will fall through the 95 screen into the bottom of the ashpit, while the larger, or unconsumed particles of fuel, will be delivered to the front of the ashpit where they may be readily removed. In some instances, it may be desired to position 100 the screen in its vertical position while shaking down the ashes, in which case the unconsumed particles of fuel will be retained upon the screen until such time as same is lowered to the inclined position. A further 105 purpose in adjusting the screen to a horizontal position is to permit convenient removal of the ashes, which are passed through the screen into the pit.

While I have shown the device as preferably constructed in the form of an attachment, it is obvious that in some instances I

may construct the same as a part of a furnace, in which case the necessity of the sides, or supporting standards, will be eliminated. In instances where the invention is placed in a circular ashpit, instead of one having straight side walls, I propose to hinge circular screen sections to the sides 9, which sections will fold over on the inclined screen to permit withdrawal of the device from the fire box. These sections may also be hinged directly to the side standards.

I claim:—
A device of the character described, comprising a frame including a pair of side standards, a normally inclined screen pivoted

at its upper end between the side standards and provided with upwardly extending sides, a furnace enveloping said screen, a hook on said furnace, and a loop carried by the free end of said screen adapted to cooperate with 20 said hook for locking said screen in a substantially horizontal position, said loop being releasable to permit said screen to be swung to inclined position to separate large particles from the ashes and deliver them to 25 the front of the ash pit.

In testimony that I claim the foregoing I have hereunto set my hand at Racine, in the county of Racine and State of Wisconsin.

HERMAN V. VROOMAN.
